UNITED STATES PATENT OFFICE.

HARVEY EZRA BROWN, OF SLOUGH, ENGLAND.

SPEED-CHANGING AND REVERSING GEAR.

SPECIFICATION forming part of Letters Patent No. 686,256, dated November 12, 1901.

Application filed March 22, 1901. Serial No. 52,424. (No model.)

To all whom it may concern:

Be it known that I, HARVEY EZRA BROWN, manager, a citizen of the United States of North America, residing at Gotha Works, 5 Slough, England, have invented certain new and useful Improvements in Speed-Changing and Reversing Gears, (for which I have made application for patent in Great Britain, No. 15,036, dated August 22, 1900,) of which the 10 following is a specification.

This invention relates to change-speed and reversing gears, the object being to provide an apparatus which will admit of an infinite gradation of speed between any desired limits 15 in either direction and which shall be compact and readily controlled by the manipulation of a single hand wheel or lever.

The invention is illustrated in the accompanying drawings, in which—

20 Figures 1 and 2 are respectively longitudinal and transverse sectional elevations, the planes of section being indicated by the lines A B C D.

In carrying my invention into effect a worm 25 or pinion *a* is fixed to the rotating shaft *b*, whence the power from the prime mover is derived and which is hereinafter called the "driving-shaft." The said worm or pinion engages with a worm-wheel or spur-wheel *c*, 30 which is preferably mounted axially upon the shaft *h*, to which it is desired to impart a variable speed and which is hereinafter called the "driven shaft," the said worm-wheel being free to rotate independently upon the said 35 shaft. Fixed to the said worm-wheel *c* or forming an integral part of same is provided a disk or plate *d*, in the face of which pins *e* are provided to carry one or more planet-wheels *f*, which revolve freely upon their 40 respective pins. The planet wheel or wheels engage simultaneously, in the first place, with a central sun-wheel *g*, which is keyed or otherwise fixed to the driven shaft *h*, and, in the second place, with an annular wheel *k*, which 45 is preferably mounted upon the driven shaft, but free to revolve independently thereon, as in the case of the worm-wheel *c*. Fixed to the annular wheel *k* or forming an integral part of same is provided a worm-wheel *l*, engaging with a worm *m*, the said worm and wheel being preferably made with such a pitch 50 that the worm-wheel on being given a tend-

ency to revolve would be very nearly or quite capable of driving the worm as desired.

Now it is evident that if the motion of the 55 driving-shaft *b* be imparted through the gearing described to the disk *d*, carrying the planet wheel or wheels *f*, the result will be to rotate the sun-wheel *g*, provided that the annular wheel *k* is stationary, it being well understood that in this form of sun-and-planet gear the annular wheel forms the fulcrum or point of purchase whence the motion of the planet-wheel reacts upon the sun-wheel. The annular wheel *k* is held stationary so long 60 as the worm-gear *l m*, fixed thereto, is not permitted to rotate. If now suitable means are provided to rotate the worm-gear *l m*, thereby releasing the annular wheel *k* at any desired gradation of speed in the same direction 65 as that in which the planet-wheel *f* revolves, it will be readily seen that complete control is obtained for the resultant speed of the sun-wheel *g*, and thereby that of the driven shaft *h*.

75 For controlling the speed of the annular wheel *k* the driving-shaft *b* is connected by bevel-gears *o p* to a shaft *q*, at one end of which is mounted a friction-disk *r*. Upon one end of the worm-shaft *s*, upon which the 80 controlling-worm *m* is mounted, is provided a friction-wheel *t*, whose periphery is in frictional contact with the friction-disk *r*. The friction-wheel is arranged to slide longitudinally along the worm-shaft upon a feather *u*, 85 and a prolongation *v* forms a sleeve in which a groove *w* is provided as a means of engagement with a lever or other device for controlling the longitudinal movement of the friction-wheel, whether the same is rotated or 90 not, as is usual in such cases. By means of the longitudinal movement described the friction-wheel *t* may be caused to travel at will across the face of the friction-disk *r* from center to periphery of the same. So long as the 95 friction-wheel, being in contact with the rotating disk, is held at the center of the latter there will be no rotation of the worm-shaft *s*, carrying the controlling-worm *m*, and consequently the annular wheel *k* remains stationary, resulting in the highest prearranged speed of the sun-wheel *g* and driven shaft *h*. If then the friction-wheel *t* be traversed across the friction-disk *r* outwardly toward its pe-

riphery, it will be readily seen that a gradually-increasing motion is imparted to the annular wheel k , producing, in effect, a differentiation in the sun-and-planet gear, with a 5 resulting and corresponding decrease of speed in the sun-wheel g and driven shaft h . By suitably arranging the proportions of the friction-gear and the extent of the longitudinal travel of the friction-wheel a point will be 10 reached in such longitudinal travel where the resulting speed of the annular wheel k will be equal to that of the disk d , carrying the planet-wheels f , which may be described as the normal or most favorable speed for running 15 the driven shaft h . Beyond this point the resulting speed of the annular wheel k will be found to exceed that of the planet-wheel disk d , and a point will be reached where the differentiation in the sun-and- 20 planet gear will cancel the turning moment of the sun-wheel g and result in cessation of movement in the driven shaft h . Beyond this again the effect will be to reverse the original direction of rotation of the driven 25 shaft.

Up to the point where the cessation of rotation of the driven shaft is attained very little, if any, power is required to rotate the annular wheel k , the motion being, in fact, 30 more of the nature of a release rather than a drive, and the friction-gear is relied on. Beyond that point when actual driving of the annular wheel is required a toothed gear x is provided, which is preferably put into operation 35 by means of a clutch y , so arranged as to come automatically into gear when the friction-wheel t has reached the limit of its outward travel.

The framework z , forming the bearings for 40 the various shafts and connecting the whole together, may be of any convenient form suitable for the purpose to which my invention may be applied, and in cases where it is desirable to exclude dirt I combine the framing 45 with a dust-proof casing arranged also to form an oil-bath for the gearing when desired.

Having now described my invention, what I claim as new, and desire to secure by Letters Patent, is—

50 1. In combination, a shaft, a sun-wheel thereon, a planet-wheel engaging therewith, a carrier for the planet-wheel, a toothed wheel meshing with the planet-wheel and means for driving the toothed wheel comprising friction driving means and positive driving means 55 and means of adjustment whereby either the positive or the friction driving means may be made to act, substantially as described.

2. In combination, the main shaft h , a sun-wheel fixed thereon, a planet-wheel meshing 60 with the sun-wheel, a disk arranged at one side of said sun and planet wheels on the shaft, and carrying the planet-wheel, a toothed wheel k surrounding the sun and planet wheels and meshing with the latter, a disk on 65 the opposite side of the sun and planet wheels from the disk first mentioned and carrying the toothed wheel, worm-gearing for each of said disks, the shafts b and s connected with the said worm-gearing, and the adjustable 70 friction driving means between the two shafts b and s , substantially as described.

3. In combination, the main shaft, a sun-wheel thereon, a planet-wheel, a loose disk on the shaft carrying said planet-wheel, a 75 toothed wheel k meshing with the planet-wheel, gearing for driving said toothed wheel k , including friction-disks, one of which is splined on its shaft to be adjusted across the face of the other friction-disk, a positively- 80 operated gear-wheel loosely running on the shaft of the adjustable friction-disk and the clutch parts between said adjustable friction-disk and the positively-operated gear, substantially as described. 85

4. In combination, the shaft, a sun-wheel fixed thereon, a planet-wheel, means for carrying and moving said planet-wheel, a toothed wheel k engaging said planet-wheel and means for driving said toothed wheel comprising a 90 shaft, a bevel-gear thereon, a friction-disk adjustably held on the said shaft, clutching parts between the friction-disk and the bevel-gear, and a second bevel-gear for driving said loose bevel-gear, said second bevel-gear carrying 95 a friction-surface for the friction-disk, substantially as described.

5. In combination, a main shaft, a toothed wheel fixed thereto, a planet-wheel in mesh with the same, a disk carrying the latter, 100 means for driving the disk including a counter-shaft b , a toothed wheel k in mesh with the planet-wheel, means for controlling the rotation thereof including a worm-shaft, a friction-wheel on the worm-shaft, a friction 105 connection between friction-wheel and the counter-shaft b and positive drive mechanism interposed between said counter-shaft b and the friction-wheel, substantially as described.

In testimony whereof I have hereunto set 110 my hand in presence of two witnesses.

HARVEY EZRA BROWN.
